UNITED STATES PATENT OFFICE.

WILLIAM JAMES PERRY MOORE, OF LONDON, ENGLAND.

PUMP.

SPECIFICATION forming part of Letters Patent No. 674,789, dated May 21, 1901.

Application filed September 29, 1900. Serial No. 31,562. (No model.)

To all whom it may concern:

Be it known that I, WILLIAM JAMES PERRY MOORE, engineer, a citizen of the United States of America, residing at 7 Sloane street, 5 London, W., in the county of Middlesex, England, have invented certain new and useful Improvements in Connection with Pumps, (for which I have made application for Letters Patent in Great Britain, No. 4,302, dated 10 March 6, 1900,) of which the following is a specification.

This invention relates to improvements in connection with pumps and the valve-chambers connected with the same, the object being to provide for a method of constructing and arranging the working barrels and the valve-casings which will obviate the disconnection of any part of the valve-chamber when the working barrel or water-cylinder is to be 15 renewed or repaired. I am also enabled to provide a convenient arrangement of valves which will facilitate their examination and renewal, with a minimum amount of interference or disconnection of jointed surfaces.

In the accompanying sheets of explanatory drawings, Figure 1 is a sectional elevation of a pump having my improvements thereon, taken on a line X X on Fig. 4 in direction of arrow 1. Fig. 2 is a side elevation, 20 and Fig. 3 is a front elevation, of the same. Fig. 4 is a plan of the pumps, showing the valve-covers in position. Fig. 5 is a sectional plan of the valve and water chambers, taken 25 through Y Y on Fig. 1. Fig. 6 is a sectional plan of the valve and water chambers, taken on Z Z on Fig. 1. Fig. 7 is a sectional view on line 7 7 of Fig. 3.

In carrying my invention into effect when providing for a vertical type of pump I form 30 my water-cylinders *a* in such a manner that they can be suspended from or independently attached to the casing or chamber *b*, in which the valves are arranged. I may make the inlet connection to the lower end of the water-cylinder *a* by means of an independent pipe, or I may provide for the passage to the end by means of a port or cored passage *c*, cast in one with the pump-cylinder or water vessel *a*. The upper end of the water vessels I make to bolt or connect onto the valve chamber or casing *b*, the valves of which

are arranged concentrically about the pump-chamber, as shown in Figs. 4, 5, and 6.

In the duplex form of pump shown in the drawings the action of each pump is similar, 55 and the parts of each pump are similarly lettered. Therefore a description of one will suffice for the other also.

The action of one pump is as follows: As indicated by the arrows in Fig. 1, water enters on the downstroke of the plunger *d* onto the top thereof through *e e* and on the upstroke is delivered from the top of the plunger through a valve *g* into a common delivery *f*. At the same time on the upstroke water enters below the plunger up through the valves *e' e'* and down the passage *c* and on the downstroke is delivered from below the plunger back through the passage *c*, past a valve *g'*, into the common delivery *f*. 70

I arrange my pumps in pairs, as shown in the accompanying drawings, to suit the well-known duplex or Worthington system of steam-cylinders, making one common water end or chamber *b* to carry both independent 75 water-barrels *a a* and the sets of working suction and delivering valves *e e' g g'*, with a common outlet or rising main passage *f*, as shown in Figs. 1 and 6. I connect the rising main branch *h* to either side of the common 80 passage *f*, placing a blank flange *k* on the side not in use. The suction connection *m* I make to the common passage *n*, as shown in Figs. 1 and 5.

I employ any ordinary type of valve in connection with my improved valve-casing and chambers, and I arrange covers *l* over each independent valve or series of valves, so that one valve removal or series of valves being removed does not disturb another valve or 90 series.

I modify the form of my valve-casing and the arrangement for securing the pump-barrels to suit the size, type, and purpose of the pump which is to be constructed. I may, for 95 example, make my suction and delivery valves in duplicate pairs and arrange them in a double circle, one circle within the other concentrically about the pump-chamber, and I actuate my pump-rods by steam-cylinders or by 100 any other well-known system of working such pumps. Similarly I employ a single barrel

instead of a pair, as shown in the accompanying drawings, where such is required for any particular purpose.

Having thus described my invention, what I claim as new, and desire to secure by Letters Patent, is—

In combination in a pump, the barrels arranged side by side, a valve-chamber at the upper ends of the said barrels common thereto, a passage from the valve-chamber to the lower end of each barrel, said valve-chamber having a common suction-passage therein extending about the said chamber, suction-

valves for each barrel supplied from the said common suction-passage, discharge-valves in the valve-chamber for each barrel, and a common delivery-passage for both barrels arranged centrally of the valve-casing, substantially as described.

In witness whereof I have hereunto set my hand in presence of two witnesses.

WM. JAMES PERRY MOORE.
